UNITED STATES PATENT OFFICE.

HENRY M. LELAND AND FRANK E. FERRIS, OF DETROIT, MICHIGAN, AS
SIGNORS TO THE LELAND & FAULCONER MANUFACTURING COMPANY,
OF SAME PLACE.

MACHINE FOR GENERATING TEETH OF BEVEL-GEARs.

SPECIFICATION forming part of Letters Patent No. 624,508, dated May 9, 1899.

Application filed February 3, 1898. Serial No. 668,931. (No model.)

To all whom it may concern:

Be it known that we, HENRY M. LELAND and FRANK E. FERRIS, citizens of the United States, residing at Detroit, county of Wayne, 5 State of Michigan, have invented a certain new and useful Improvement in Machines for Generating Teeth of Bevel-Gears; and we declare the following to be a full, clear, and exact description of the invention, such as 10 will enable others skilled in the art to which it appertains to make and use the same, reference being had to the accompanying drawings, which form a part of this specification.

Our invention has for its object a novel 15 process and machine for forming or generating the teeth of bevel-gears.

Our invention more particularly has in view the generation of bevel-gears for chainless bicycles, although we do not limit ourselves 20 solely thereto. It is well understood that great difficulty has heretofore been experienced in accurately and economically forming bevel-gears, especially for this purpose. That the teeth of bevel-gears cannot be accurately milled has heretofore been pointed 25 out as a very serious obstacle to the practical success of gears of this class in supplanting the chain-driven gear.

It is well known that it has been customary 30 to form and accurately finish the teeth of bevel-gears from iron or soft steel and then to subject the gears to the proper hardening process; but it has been found that however perfect the teeth may have been formed and 35 finished in the soft metal when these gears have been subjected to the process of heating and hardening the required accuracy and perfection have been destroyed and the working faces or surfaces of the teeth are not concentric with the axis of the gears and the spacing 40 and form of the teeth are untrue and imperfect, and consequently useless for the purposes above mentioned. Our invention, however, contemplates forming the gears approximately correct by ordinary means in soft steel 45 or in the soft iron and then correcting both the original errors in the form of teeth cut by milling-cutters or other means and the errors resulting from heating and hardening them,

and by this means to generate bevel-gears 50 that shall be perfect and true after being hardened, and thus securing a product heretofore unknown to the art. It is obvious that after the gears have been properly hardened a milling-tool or other ordinary means commonly used in forming the teeth of bevel-gears can no longer be employed in the correction of the errors above mentioned, so that other means must be found adapted to correcting and truing the gears after they have 55 been hardened in order to carry out our improved process. We accomplish this result by means of a suitable grinding-wheel adapted to act upon the hardened gears in such a manner as to correct all errors in the teeth 60 after the gears have been hardened, and so render the completed gears perfect, thereby preventing waste, promoting economy, and securing superior utility and efficiency and rendering the application of bevel-gears to bicycles more practicable and satisfactory than 65 has heretofore been the case.

To these ends our invention consists of the process and mechanism herein described and claimed, and illustrated in the accompanying 70 drawings, in which—

Figure 1 is a side elevation. Fig. 2 is a plan view. Fig. 3 is a rear elevation. Fig. 4 is a detail view in elevation of the indexing mechanism. Fig. 5 is a detail view, in side 80 elevation, of the same. Fig. 6 is a detail view in plan, illustrating the same. Fig. 7 is a view of the cam for moving the grinding-wheel toward and away from the gear. Fig. 8 is an enlarged front elevation showing the 85 slide that carries the grinding-wheel. Fig. 9 is a view in section on the line 9 9, Fig. 8. Fig. 10 is a detail view showing the former and the mechanism contacting therewith. Fig. 11 is a view of the same at right angles 90 to Fig. 10. Fig. 12 is an inverted plan of the same. Fig. 13 is a detail view of the cam for reciprocating the grinding-wheel. Fig. 14 is a detail view illustrating the changed position of the grinding-wheel to grind on the adjacent faces of the two adjacent teeth. Fig. 15 is a detail view showing devices for locking 95 the micrometer-screws R². Fig. 16 is an

enlarged plan view of the device for holding the former against the roll. Fig. 17 is an enlarged view of the same in side elevation. Fig. 18 is a detail view in elevation, showing the device for setting or testing the adjustment of the grinding-wheel. Fig. 19 is a plan view of the same. Fig. 20 is an end view of the mechanism illustrated in Fig. 8.

In the drawings, A represents any suitable support or frame.

B denotes an arbor to carry a bevel-gear, (indicated at B'). The gear is held upon the arbor in any suitable manner. The arbor B is engaged in a spindle B² in any suitable manner. For example, said spindle may be constructed with an orifice to receive the adjacent end of the arbor, as indicated by the dotted lines at B⁴, Fig. 1. B³ is an index-plate to space the teeth, said plate carried on the spindle B², and by means of which said spindle, with the arbor, is rotated step by step. The spindle and arbor are given a rocking movement by means of an oscillatory arm B⁶, carrying at its outer end a former B⁷, said former being an enlarged reproduction or pattern approximating the form of a correct tooth upon the gear or so shaped as to give a correct form to the teeth of the gear in the operation of the machine. The bearing B⁵ of the spindle B² is provided with forks b b at its forward end, said forks fulcrumed, as indicated at b', in line with the cone center of the gear, the cone center being indicated at the intersection of the dotted lines in Fig. 2, as at Q. The bearing B⁵ is also carried rearward toward the opposite end of the spindle B², as shown more particularly in Fig. 1. The rear end of the bearing B⁵ is secured in any suitable manner upon a quadrant B⁸, as by bolts b², entering a T-shaped slot b⁴ in the quadrant. The quadrant B⁸ is formed with a guide-arm B¹⁰, in which the outer end of the lever D is guided, as indicated more particularly in Fig. 2. The guide-arm B¹⁰ is provided with a gib b⁵.

The support or frame A is provided with brackets, (indicated at a,) upon which said forks are fulcrumed. By this means the arbor is oscillated upon said fulcrum-points b', as may be required, to bring gears of different sizes and angles into proper position.

C is a rotatable grinding-wheel, made of any suitable material and having a reciprocatory movement on the cone line of the gear.

C' is the shaft of the grinding-wheel, which may be driven by any suitable device, as by a pulley C² thereupon actuated from any suitable source of power.

D is a lever made oscillatory on line with the cone center of the gear and provided with a slide D', carrying the grinding-wheel. Said lever is fulcrumed, as indicated at d, in line with the cone center of the gear and is provided with ways d', in which a slide D' carrying the grinding-wheel, reciprocates. The slide D' is provided with a suitable housing D² to carry the shaft C' of the grinding-

wheel. To reciprocate the slide D', carrying the grinding-wheel on the cone line of the gear, any suitable means may be provided, 70 as a cam E, upon a rotatable shaft E', which is driven by a pulley E², which may be belted with any suitable source of power, as with a counter-shaft. The slide D' is provided with a cam-roll d², projecting into a suitable cam-groove e of the cam E. (Shown in Fig. 13.) The lever D, carrying the slide and the grinding-wheel, is also given an oscillatory movement to carry the grinding-wheel toward and away from the bevel-gear—as, for example, 80 when the gear is to be rotated. This oscillatory movement may be accomplished in any suitable manner, as by a cam F upon a shaft f, the cam F being indicated in detail in Fig. 7. The lever D is provided with a cam-roll 85 d³, projecting into a cam-groove f' of the cam F. The shaft f is preferably actuated by a gear F', meshing with a pinion F² upon a shaft f², which latter shaft may be driven in any suitable manner, as by a pulley F², which 90 may be belted to a counter-shaft. The pinion F² is interposed to reduce the speed of the shaft f and cam F.

D³ is an oscillatory arm pivoted, as indicated at d⁴, upon an extended portion of the 95 lever D, said arm D³ carrying a roll, (indicated at D⁴), said roll contacting with the former B⁷. As the outer end of the lever D, adjacent to the former, is carried downward or toward the spindle B² by means of the cam F, as hereinbefore described, the roll D⁴ will travel about the edge of the former, giving a corresponding oscillatory movement to the arm B⁶ and a rocking movement to the spindle B². By this means it will be evident that 105 the tooth being operated upon by the grinding-wheel will be given a rocking movement to secure the proper curvature of the tooth in the action of the grinding-wheel thereupon. It will be understood that the grinding-wheel contacts with the tooth in operation on the edge of the wheel, as indicated in Fig. 14, for example, and by thus rocking the gear the proper curvature to each tooth will thereby be secured in a perfect manner. 110 The parts are so arranged that the roll D⁴ will always contact with the former on a line passing through the cone center, said line being indicated by the single arrow-head. As the parts are located in the machine illustrated in the drawings this line is in a vertical plane. It might, however, be in any other desired plane. It will be evident from Fig. 3, for example, that when the end of the lever D is lifted so as to carry the grinding- 115

wheel away from the gear the arm D³, with the roll D⁴, will be carried into position, (indicated in dotted lines in Fig. 3,) the roll D⁴ being in position, whereby the operator may oscillate the arm D³ to either side the 120 line indicated by the single arrow-head, so as to contact as it descends with either edge of the former, the former being rocked when the roll D⁴ is lifted, so that its outer point 125

will be on said line, whereby the grinding-wheel may be guided to act on either side a given tooth, as may be desired. The center of the arbor carrying the gear is also on the line indicated by the single arrow-head, as is also the contacting or grinding edge of the grinding-wheel. It will be observed that the spindle carrying the index-plate B³ also has its center on said line. When the roll D⁴ is lifted, a step-by-step rotation is given to the spindle B² and the arbor carried thereby to turn the gear B' from one tooth-space to another. When so moved, the index-plate is locked in its relation to the former. The index-plate is spaced or toothed accurately on its periphery, as shown, to correspond with gears having the same number of teeth or multiples thereof, the index-plate being interchangeable on the spindle B², so that an index-plate corresponding to any given gear to be formed may be engaged upon said spindle. The index-plate is provided with a ratchet-wheel, (indicated at G,) with which engages a pawl G' to give rotation to said plate. The pawl is carried by a bar G², having an adjustable engagement upon a slide G³, as indicated at g. The slide G³ reciprocates upon a guide G⁴, carried by or integral with the bearing B⁵. The slide G³ is actuated by a lever H, fulcrumed to the bearing B⁵, as indicated at h, its opposite end engaging a collar H' upon a shaft H², forming the pivot for the adjacent portion of the forks b of said bearing, and upon which pivots the adjacent portion of said fork is fulcrumed, as indicated at b', as hereinbefore described. The longitudinal center of the shaft H² is on a line passing through the cone center of the gear, which line is indicated in the drawings by the double arrow-heads and intersects at the cone center the line indicated by the single arrow-head. Engaging said collar H' is an additional lever H³, which is fulcrumed, as shown at h', to the support A, the opposite end of the lever H³ engaging a cam-groove j of a cam J, engaged upon the shaft f, which carries the cam F. The cam F is provided with a concentric portion, as shown in Fig. 7, the parts being so arranged that when the cam F is raised the adjacent end of the lever D and the cam-roll of said lever will ride in said concentric portion of the cam-groove, during which time, obviously, the lever is at rest. Meanwhile the cam J actuates the lever H³, shifting the collar H' on the shaft H², thereby shifting the lever H and actuating the slide G³ to actuate the pawl G' to correspondingly actuate the ratchet-wheel G. The opposite movement of the related parts will of course retract the slide G³ and the pawl G'. To regulate the throw of the pawl or its engagement with the ratchet-wheel, a governing-slide g' may be employed, which may be carried by the guide G⁴. The slide g' may be held in place by a screw g² and may be so adjusted that when the pawl is retracted it

will lift the pawl out of engagement with the ratchet-wheel and will obviously prevent the pawl from engaging the ratchet-wheel in the opposite movement thereof until the end of the pawl has passed beyond the end of said slide. In this manner the engagement of the pawl with the ratchet-wheel may be governed as may be desired to throw the ratchet-wheel to approximately the correct position.

To accurately locate the index-plate, a plunger K is provided to engage any given space upon the periphery of the index-plate. The adjacent end of said plunger is wedge-shaped, so as to readily engage a given space upon said plate. The plunger is carried by an arm K', sleeved upon the spindle B², and upon which arm K' the former-arm B⁶ is secured, as by bolts k. The former-arm B⁶, with its former, is made interchangeable, as a different-shaped former will be required on different gears, and by uniting the former-arm B⁶ to the arm K' it may readily be interchanged as desired. The plunger K may be actuated in the following manner:

L is an oscillatory arm fulcrumed, as at l, upon the slide G³, said arm formed with a projecting cam-flange portion l'. L² denotes a bell-crank fulcrumed, as at l', to the guide G⁴. The bell-crank L² is provided at one extremity with a shoulder l⁴ to engage the cam-flange l'. The opposite end of the bell-crank is engaged with a plunger-bar K². As shown in Fig. 6, the plunger K and the plunger-bar K² have a toothed engagement the one with the other in such a manner that as the plunger-bar K² is reciprocated in the actuation of the bell-crank L² the plunger K may be forced out of engagement with the index-plate, a retracting-spring K³ restoring the plunger into engagement with the index-plate. It will also be observed that the toothed engagement of the plunger with the plunger-bar is such that when the arm K' is oscillated by means of the plunger-arm B⁶ the plunger K may readily ride out of engagement with the plunger-bar K², the plunger remaining in locked position in relation to the index-plate. A spring K⁴ serves to retract the plunger-bar K² into normal position. Adjusting-nuts K⁵, bearing against a bracket K⁶, serve to adjust the position of the plunger-bar. As the oscillatory arm L is reciprocated or carried backward and forward upon the slide G³ the shoulder l⁴ upon one movement of the slide L will obviously ride under the cam-flange l' and there past, the opposite movement of the arm L causing the shoulder l⁴ to ride upon the upper or opposite edge of the cam-flange l'. In the position shown in Fig. 4 the first movement of the slide G³ will obviously cause the shoulder l⁴ to ride under the cam-flange l', thereby tilting the slide L without actuating the bell-crank. After the arm L has retracted beyond the shoulder l⁴ the opposite movement of the slide G³ will cause the shoulder l⁴ to ride upon the upper edge of the cam-

flange, thereby tilting the bell-crank L^2 to retract the plunger-bar K^2 and the plunger K . A spring k^5 serves to retract the arm L .

The arm K' preferably has a divided bearing on a sleeve or bushing B^9 upon the spindle B^2 , said sleeve or bushing having a fixed engagement with the bearing B^6 . A spring g^8 serves to keep the pawl G' into normal engagement with the ratchet G . In order to removably engage the index-plate in place upon the spindle B^2 , said spindle may be provided with a flange, (indicated at M .) The ratchet-wheel G may be formed, as of a ring, integral with the index-plate to set over the flange M . The index-plate is also provided with a suitable number of arc-shaped slots, (indicated at m .) through which screws m' may be passed, engaging the index-plate with the flange M . By removing said screws the plate, with its ratchet-wheel or ring, may readily be detached from the spindle. By means of said arc-shaped slot also the index-plate when applied to the flange M may be turned into proper position to aline the teeth of the index-plate with the teeth of the gear to be ground.

When the arm D^3 has been adjusted into desired position, as hereinbefore described, it may be locked upon the projecting end of the lever-arm D by means of a suitable latch or spring-plunger, (indicated at d^6 .)

By making the cam E , as indicated in Fig. 3, with a heart-shaped cam-groove e the slide upon the lever D , carrying the grinding-wheel, will be reciprocated with uniform speed. The oscillatory arm D^3 is guided, as shown at d^8 , in its oscillation upon a gib d^7 , secured upon the lever D . Upon the end of the lever D , adjacent to the arm D^3 , are engaged stop-plates N , which may be secured in place by screws n . The arm D^3 is provided with a pin (indicated at N') to contact with the stop-plates N . As the arm D^3 is shifted upon either side of the former, as hereinbefore explained, the stop N' , striking against the corresponding stop-plate N , will bring the periphery of the roll D^4 upon the line indicated by the single arrow-head hereinbefore described.

To keep the former in contact with the roll D^4 and to bring the point of the former to a central position on a line passing through the cone center when the roll is not acting thereupon, any suitable means may be provided— as, for example, the guide P , secured to the frame of the machine and carrying slides P^1 P^2 , each of said slides carrying a sheave p . P^3 is a connecting-rod suitably connected at one end with the arm of the former and at the other end with a sliding stud p' , reciprocatory in said guide and arranged to contact with either of said slides, and thereby actuate said slides in a corresponding direction. To one of the slides is attached a cord P^4 , said cord running over said sheaves and attached at its opposite end to a spring, as indicated at P^5 . Obviously a weight might be substi-

tuted for the spring, if desired. P^6 is a stop located intermediate the ends of the guide between the adjacent ends of said slides to limit the inward movements of said slides. When the former is moved away from the line passing through the cone center in either direction, the connecting-rod P^3 will be moved in a corresponding direction, causing the sliding stud p' to contact with the corresponding slide to move said slide and take up the cord. In so doing the spring is obviously extended, and when extended will retract the corresponding slide when free to move. In this manner the former will be held properly in contact with said roll and on said center line when the roll is out of contact therewith.

The front end of the slide D' is provided with a transverse guide d^{10} , upon which is a laterally-reciprocating cross-head R , in sliding engagement therewith, said cross-head constructed with a hub r .

R' is a guide carrying the housing D^2 , hereinbefore mentioned, which housing carries the grinding-wheel. The cross-head R is limited in its travel by means of stop-screws R^2 , the same being preferably micrometer adjusting-screws to accurately limit the lateral adjustment of the grinding-wheel carried by said housing, so as to bring the cutting edge of the grinding-wheel upon the center line indicated by the single arrow-head passing through the cone center of the gear. The screws R^2 are locked in their adjustment in any suitable manner, as by means of plugs r' engaging the threads of said screws, locking-screws r^2 being engaged upon said plugs. By this means the grinding-wheel may be laterally adjusted with greatest accuracy. The ends of the micrometer-screws preferably enter recesses r^3 in the hub of the cross-head, said recesses forming a housing to protect the points of the micrometer-screws against any foreign matter that might prevent the accurate adjustment of the cross-head.

R^4 is a bolt securing the guide R' to the cross-head R . Said cross-head is formed with an arc-shaped slot R^5 , through which the bolt R^4 passes. The guide R' has projecting tongues r^4 projecting into the arc-shaped slot R^5 . By this means the guide R' may be tilted in the arc of a circle in said arc-shaped slot R^5 to tilt the grinding-wheel, and thereby produce the necessary clearance of the wheel in its operation upon the teeth and the gear, as illustrated more specifically in Fig. 14, to shape the teeth of the gear in required form. Upon the end of the bolt R^4 is a nut R^6 , actuated by a lever R^7 , for tightening the bolt to lock the guide R' to the cross-head R .

R^8 is a screw for traversing and holding the cross-head in contact against the micrometer-screws.

To give the housing D^2 a vertical movement on the guide R' , a screw S may be employed, said screw preferably being a micrometer-screw, to vertically adjust the grinding-wheel, so that as said grinding-wheel reciprocates it

will reciprocate on a line passing through the cone center. The guide R' is provided with a plate r⁶, through which said screw passes, the screw being shouldered upon said plate 5 and also threaded into the housing carrying the grinding-wheel. By this means as the screw is adjusted the housing will move on the guide R'. By this means the grinding-wheel may be vertically adjusted to any required adjustment—as, for example, to compensate for any wear upon the grinding-wheel, as well as from any other cause.

To insure the grinding-wheel being accurately adjusted or set so that its cutting edge 15 will be upon a cone line of the gear both vertically and horizontally, a bracket T may be employed. The ends d¹¹ d¹² of the lever D, forming the bearings on the shaft H², may be provided the one with V-shaped grooves (indicated at t) and with threaded sockets (indicated at t') to receive a clamping-screw T¹, passed loosely through the bracket and having a clamping-collar t². At the opposite end 20 the bracket is secured upon the portion d¹² by a clamping-screw T², entering the threaded recess t³. The end of the bracket adjacent to the grinding-wheel when in place is provided with a longitudinal straight-edge or tongue T⁴, either lateral face of which might 25 be located on the line indicated by the single arrow-head passing through the cone center of the gear and to which line the grinding-wheel is to be adjusted. The bracket adjacent to the grinding-wheel is also constructed 30 with horizontal shoulders t⁴, said shoulders when in place being on a cone line indicated by the triple arrow-heads in Fig. 18. The bracket is constructed with a V-shaped lug (indicated at t⁵) to enter and locate in the 35 grooves t of the part d¹¹. It will be evident that when said lug t⁵ has entered the right-hand groove shown in Fig. 18 one lateral face of the tongue T⁴ will be on the line indicated by the single arrow-head and the shoulder t⁴ thereabove will be on a horizontal line indicated 40 by the triple arrow-heads. When the lug t⁵ engages in the left-hand groove shown in Fig. 18, the opposite lateral face of the tongue T⁴ will be on the line indicated by the 45 single arrow-head and the horizontal shoulder thereabove will be on the line of the triple arrow-heads. By means of a straight-edge or parallel piece T⁵ the operator may readily test the position of the grinding edge of the grinding-wheel by applying said parallel piece 50 against the tongue and corresponding shoulder of the bracket.

In the operation of the machine the operator puts the bevel-gear upon the arbor and 60 properly alines it into proper relation to the teeth of the index-wheel. It will be obvious that the grinding-wheel must be speeded faster than other parts of the machine and that the wheel must be set into rotation before the other parts begin to move. The lever D will be given an oscillatory movement and the grinding-wheel a reciprocatory move-

ment on the cone line of the gear simultaneously. It will be evident that thereby the former will be caused to act to rock or partially rotate the arbor carrying the gear, for the purposes hereinbefore mentioned. In due succession a vertical reciprocation will also be given to the grinding-wheel, and when said wheel is in raised position a step-by-step movement will be given to the bevel-gear by means of the index-plate above described and mechanism connected therewith.

The various parts of the machine, it will be understood, will be operated in relation 80 one to another to produce the required results either synchronously or in due succession, as required. It will be perceived that the grinding-wheel has a rotary movement, a reciprocatory movement on the cone line of 85 the gear, a vertical movement, and a swivel movement to give clearance thereto in its work on the side of the teeth of the gear, while it also may be laterally and vertically adjusted. It will be evident that the bracket 90 T is removable when the machine is in operation.

It is well known that various things destroy the efficiency of bevel-gears as they have ordinarily been constructed, wherein the gears 95 have been formed and finished of soft metal and then hardened by heating and cooling the same—as, for example, the working surfaces of the teeth have been thrown out of concentricity with the axis. There is also a 100 winding or twisting or warping of the faces of the gear as a whole, in consequence of which one tooth may lean in one direction and an adjacent tooth in another direction. So, also, the spacing or pitch of adjacent teeth 105 is changed in the hardening process. In consequence of these changes no bevel-gear can be made by the ordinary means heretofore in use theoretically or geometrically correct; but by our improved process and mechanism 110 the gears may be made both theoretically and geometrically correct and with facility.

What we claim as our invention is—

1. In a machine for generating the teeth of bevel-gears, means to carry a bevel-gear, a 115 rotatable grinding-wheel reciprocatory on a cone line of the gear in the operation of grinding the gear, and means to direct the position of the teeth of the gear in the operation of grinding the gear to give the correct curvature to said teeth, substantially as set forth.

2. In a machine for generating the teeth of bevel-gears, means to carry a bevel-gear, and a rotatable grinding-wheel having a movement toward and away from the bevel-gear, 125 said grinding-wheel also made reciprocatory on a cone line of the gear in the operation of grinding the gear, and having a movement from the peripheral edge of the tooth toward the axis of the gear, substantially as set forth. 130

3. In a machine for generating the teeth of bevel-gears, the combination with a rotatable grinding-wheel reciprocatory on a cone line of the gear in the operation of grinding the

gear, of a rotatable arbor to carry a gear, means to give to said arbor a step-by-step rotation, and means to rock said arbor in the operation of grinding the gear, substantially as set forth.

4. In a machine for generating the teeth of bevel-gears, a device to carry a gear, a rotatable grinding-wheel reciprocatory on a cone line of the gear in the operation of grinding the gear, and a former to actuate said device, substantially as set forth.

5. In a machine for generating the teeth of bevel-gears, a rotatable arbor to carry a gear, an arm to actuate the arbor, and a non-revoluble former to actuate said arm, substantially as set forth.

6. In a machine for generating the teeth of bevel-gears, a device to carry a bevel-gear, a rotatable grinding-wheel reciprocatory on a cone line of the gear in the operation of grinding the gear, and means to tilt the grinding-wheel in a direction at right angles to the cone line of the gear, substantially as set forth.

7. In a machine for generating the teeth of bevel-gears, means to carry a bevel-gear, a lever oscillatory on a line passing through the cone center of the gear, and a grinding-wheel carried by said lever having a series of reciprocatory movements in the operation of grinding the gear, substantially as set forth.

8. In a machine for generating the teeth of bevel-gears, the combination of a rotatable grinding-wheel having a series of reciprocatory movements on a cone line of the gear in the operation of grinding the gear, an arbor to carry a gear, and an indexing device to rotate said arbor to space the teeth of the gear, substantially as set forth.

9. In a machine for generating the teeth of bevel-gears, the combination of a rotatable grinding-wheel reciprocatory in the operation of grinding the gear, a device to carry a bevel-gear, a lever oscillatory on a line passing through the cone center of the gear, and means to oscillate said lever, substantially as set forth.

10. In a machine for generating the teeth of bevel-gears, a device to carry a bevel-gear, a lever oscillatory on a line passing through the cone center of the gear, a former to actuate said device, and a roll carried by said lever to contact with said former, substantially as set forth.

11. In a machine for generating the teeth of bevel-gears, an arbor to carry a bevel-gear, a lever oscillated on a line passing through the cone center of the gear to move toward and away from the gear, and means to give a step-by-step rotation to said arbor when said lever is moved away from the gear, substantially as set forth.

12. In a machine for generating the teeth of bevel-gears, an arm to actuate the arbor, a former carried by said arm, and means cooperating with said arm to actuate said arm, substantially as set forth.

13. In a machine for generating the teeth

of bevel-gears, a rotatable arbor to carry a bevel-gear, an index-plate rotatable with said arbor, an arm to actuate said arbor, and a former to actuate said arm, substantially as set forth.

14. In a machine, for generating the teeth of bevel-gears, a rotatable arbor to carry a bevel-gear, an index-plate rotatable with said arbor, an arm to actuate said arbor, a former to actuate said arm, and means to lock said arm upon the index-plate, substantially as set forth.

15. In a machine for generating the teeth of bevel-gears, a rotatable arbor to carry a bevel-gear, an index-plate rotatable with said arbor, means to give a step-by-step rotation to said arbor, an arm to actuate said arbor, a former to actuate said arm, and means to lock said arm upon the index-plate after each step-by-step movement thereof, substantially as set forth.

16. In a machine for generating the teeth of bevel-gears, means to carry a bevel-gear, a rotatable grinding-wheel, and means to reciprocate the grinding-wheel on a cone line of the gear in the operation of grinding the gear, said grinding-wheel being laterally and vertically adjustable, substantially as set forth.

17. In a machine for generating the teeth of bevel-gears, means to carry a bevel-gear, a laterally-adjustable grinding-wheel, and means to reciprocate the grinding-wheel on a cone line of the gear in the operation of grinding the gear, and adjustable stops to govern the adjustment of the grinding-wheel, substantially as set forth.

18. In a machine for generating the teeth of bevel-gears, means to carry a bevel-gear, a rotatable grinding-wheel, and means to reciprocate the grinding-wheel on a cone line of the gear in the operation of grinding the gear, a device to laterally adjust said grinding-wheel, and means to cover said adjusting devices, substantially as set forth.

19. In a machine for generating the teeth of bevel-gears, means to carry a bevel-gear, and a grinding-wheel arranged to actuate upon the cone line of the gear, substantially as set forth.

20. In a machine for generating the teeth of bevel-gears, the combination of means to carry a bevel-gear, a grinding-wheel, and means to reciprocate the grinding-wheel on a cone line of the gear in the operation of grinding the gear, said gear and grinding-wheel the one arranged to rock in relation to the other in the operation of grinding the gear to form the proper curvature of the teeth upon said gear, substantially as set forth.

21. In a machine for generating the teeth of bevel-gears, the combination of means to carry a bevel-gear, a grinding-wheel, and means to reciprocate the grinding-wheel on a cone line of the gear in the operation of grinding the gear, said gear and grinding-wheel the one arranged to have a rocking movement in the operation of grinding the gear to form the

- proper curvature of the teeth upon said gear, substantially as set forth.
22. In a machine for generating the teeth of bevel-gears, the combination of means to carry a bevel-gear, an adjustable grinding-wheel to act upon the teeth of the gear, means to reciprocate the grinding-wheel on a cone line of the gear in the operation of grinding the gear, and adjustable stops to regulate the adjustment of the grinding-wheel, substantially as set forth.
23. In a machine for generating the teeth of bevel-gears, means to carry a bevel-gear, a laterally-adjustable grinding-wheel, and means to reciprocate the grinding-wheel on a cone line of the gear in the operation of grinding the gear, and adjusting-screws to laterally adjust said wheel, substantially as set forth.
24. In a machine for generating the teeth of bevel-gears, the combination of a rotatable grinding-wheel, a quadrant, and an arbor to carry a gear adjustable upon said quadrant, said arbor having a rocking movement in the operation of grinding the gear, substantially as set forth.
25. In a machine for generating the teeth of bevel-gears, an oscillatory arbor to carry the gear, and a grinding-wheel to act upon the teeth of the gear having a reciprocatory movement in the operation of grinding the gear, substantially as set forth.
26. In a machine for generating the teeth of bevel-gears, an arbor to carry the gear, a grinding-wheel, reciprocatory in the operation of grinding the gear and a spindle to carry the arbor, substantially as set forth.
27. In a machine for generating the teeth of bevel-gears, an arbor, a spindle to carry the arbor having a rocking movement in the operation of grinding the gear, and a bearing to carry the spindle, said spindle fulcrumed on a line passing through the cone center of the gear, substantially as set forth.
28. In a machine for generating the teeth of bevel-gears, a quadrant, an arbor, a spindle to carry the arbor having a rocking movement in the operation of grinding the gear, and a bearing to carry the spindle adjustable on said quadrant, substantially as set forth.
29. In a machine for generating the teeth of bevel-gears, a rotatable grinding-wheel reciprocatory in the operation of grinding a gear an arbor, an index-plate, and pawl-and-ratchet mechanism to actuate said plate, substantially as set forth.
30. In a machine for generating the teeth of bevel-gears, a rotatable grinding-wheel reciprocatory in the operation of grinding a gear an arbor, an index-plate, a reciprocatory locking-plunger to lock said plate, and means to actuate said plunger, substantially as set forth.
31. In a machine for generating the teeth of bevel-gears, a rotatable grinding-wheel reciprocatory in the operation of grinding a gear an arbor, an index-plate, an oscillatory lock-
- ing device, and means to reciprocate the locking device, substantially as set forth.
32. In a machine for generating the teeth of bevel-gears, a rotatable grinding-wheel reciprocatory in the operation of grinding a gear an arbor, an index-plate, an oscillatory arm, and a locking device carried by said arm to lock said plate, substantially as set forth.
33. In a machine for generating the teeth of bevel-gears, a rotatable grinding-wheel reciprocatory in the operation of grinding a gear an arbor, and index-plate, an oscillatory locking-plunger, and a reciprocatory slide to engage and actuate said plunger substantially as set forth.
34. In a machine for generating the teeth of bevel-gears, a rotatable grinding-wheel reciprocatory in the operation of grinding a gear an arbor, an index-plate, pawl-and-ratchet mechanism to actuate said plate, and a reciprocatory slide to carry said pawl, substantially as set forth.
35. In a machine for generating the teeth of bevel-gears, means to carry a gear, an index-plate, a slide to actuate said plate, a shaft on a line passing through the cone center of the gear, a shifting device upon said shaft, a cam, and levers connecting said cam and slide with said shifting device, substantially as set forth.
36. In a machine for generating the teeth of bevel-gears, a rotatable grinding-wheel reciprocatory in the operation of grinding a gear a device to carry a gear, and a toothed index-plate having an adjustable connection with said device to give thereto a step-by-step movement, whereby the teeth of the index-plate may be alined with the teeth of the gear, substantially as set forth.
37. In a machine for generating the teeth of bevel-gears, a device to carry a gear, a former-arm to actuate said device, and an intervening arm connecting the former-arm with the gear-carrying device, substantially as described.
38. In a machine for generating the teeth of bevel-gears, a spindle to carry the gear, and an interchangeable former-arm provided with an oscillatory former engaged upon said spindle, substantially as set forth.
39. In a machine for generating the teeth of bevel-gears, means to carry a bevel-gear, means to rock said gear in the operation of the machine, and an oscillatory former to actuate the gear, substantially as set forth.
40. In a machine for generating the teeth of bevel-gears, means to carry a gear, means to rock said gear in the operation of the machine, a grinding-wheel, and a former to govern the position of the gear whereby the action of the wheel will produce the correct curvature to the teeth of said gear, substantially as set forth.
41. In a machine for generating the teeth of bevel-gears, means to carry a bevel-gear, a rotatable grinding-wheel reciprocatory in

the operation of grinding a gear, an oscillatory former to govern the action of the grinding-wheel upon the gear, and a traveling device to actuate said former, substantially as set forth.

42. In a machine for generating the teeth of bevel-gears, means to carry a bevel-gear, a grinding-wheel, a former, an oscillatory lever to carry the grinding-wheel, and a traveling device carried by said lever to actuate said former, substantially as set forth.

43. In a machine for generating the teeth of bevel-gears, means to carry a gear, a grinding-wheel, a former to govern the action of the grinding-wheel upon the gear, and an oscillatory traveling device to actuate said former, substantially as set forth.

44. In a machine for generating the teeth of bevel-gears, means to carry a gear, a grinding-wheel, a former to govern the operation of the grinding-wheel upon the gear, an oscillatory traveling device to actuate said former, and means to limit the oscillation of said traveling device, substantially as set forth.

45. In a machine for generating the teeth of bevel-gears, means to carry a bevel-gear, a former, and a device to travel on a line passing through the cone center of the gear to actuate said former, substantially as described.

46. In a machine for generating the teeth of bevel-gears, means to carry a bevel-gear, a former, an oscillatory lever to carry a grinding-wheel, an oscillatory arm carried by said lever, and a traveling device carried by said arm to actuate said former, substantially as described.

47. In a machine for generating the teeth of bevel-gears, means to carry a gear, a former, an oscillatory lever to carry a grinding-wheel, an oscillatory arm carried by said lever, a traveling device carried by said arm to actuate said former, and means to limit the oscillation of said arm, substantially as set forth.

48. In a machine for generating the teeth of bevel-gears, a device to carry a gear, a non-revolute former to actuate said device, and means to oscillate the former in the operation of grinding the gear, said former centering on a line passing through the cone center of the gear, substantially as set forth.

49. In a machine for generating the teeth of bevel-gears, the combination of a device to carry a gear, a non-revolute former, and means to hold the former when in normal position on a line passing through the cone center of the gear, substantially as set forth.

50. In a machine for generating the teeth of bevel-gears, the combination of a device to carry a gear, a non-revolute former oscillatory in the operation of grinding the gear, a traveling device to actuate said former, and means to hold the former in the operation of the machine in contact with said traveling device, substantially as set forth.

51. In a machine for generating the teeth of bevel-gears, the combination of a device

to carry a gear, a grinding-wheel having a vertically-reciprocatory movement, a former, a traveling device to actuate the former, and vertically with the grinding-wheel, and means to hold the former in contact with the traveling device and to restore the former on a line passing through the cone center of the gear when the traveler is raised out of contact therewith, substantially as set forth.

52. In a machine for generating the teeth of bevel-gears, the combination of a device to carry a gear, a former to actuate the gear, a traveling device to actuate the former, a guide, slides engaged with said guide, sheaves carried by said slides, a connecting-rod connected with the former to actuate said slides, a cord engaged with one of said slides and passing over said sheaves, a tension device connected with the opposite end of said cord, and a stop between the adjacent ends of said slides, substantially as set forth.

53. In a machine for generating the teeth of bevel-gears, a grinding-wheel, a device to carry the grinding-wheel, a guide carrying said device, a reciprocatory cross-head carrying said guide, and means to limit the movement of the cross-head, substantially as set forth.

54. In a machine for generating the teeth of bevel-gears, means to carry a gear, a laterally-adjustable grinding-wheel, a device to carry the grinding-wheel, a guide carrying said device, a reciprocatory cross-head, means to limit the movement of the cross-head to secure the lateral adjustment of the grinding-wheel to bring the cutting edge of the grinding-wheel upon a line passing through the cone center of the gear, substantially as set forth.

55. In a machine for generating the teeth of bevel-gears, a grinding-wheel, a device to carry the grinding-wheel having a reciprocatory movement in the operation of grinding the gear, a guide carrying said device, a reciprocatory cross-head, screws to limit the movement of said cross-head, and means to lock said screws, substantially as set forth.

56. In a machine for generating the teeth of bevel-gears, a grinding-wheel having a reciprocatory movement in the operation of grinding the gear, and means to laterally adjust said wheel to bring its cutting edge upon a line passing through the cone center of the gear, substantially as described.

57. In a machine for generating the teeth of bevel-gears, a grinding-wheel having a reciprocatory movement in the operation of grinding the gear, a housing to carry said wheel, a guide to carry said housing, a cross-head to carry said guide, a slide to carry said cross-head, and means to limit the movement of said cross-head upon said slide, substantially as described.

58. In a machine for generating the teeth of bevel-gears, a grinding-wheel having a reciprocatory movement in the operation of grinding the gear, a housing to carry said

wheel, a guide to carry said housing, a cross-head to carry said guide, a slide to carry said cross-head, and means to engage said guide upon said cross-head, substantially as set forth.

59. In a machine for generating the teeth of bevel-gears, a grinding-wheel having a reciprocatory movement in the operation of grinding the gear, a housing to carry said wheel, a guide to carry said housing, a cross-head to carry said guide formed with an arc-shaped slot, a slide to carry said cross-head, and a bolt passing through said slot engaging said guide upon said cross-head, whereby the 10 guide may be tilted in the arc of a circle to tilt the grinding-wheel, substantially as set forth.

60. In a machine for generating the teeth of bevel-gears, a grinding-wheel having a reciprocatory movement in the operation of grinding the gear, a housing to carry said wheel, a guide to carry said housing, a cross-head to carry said guide, means to reciprocate the cross-head, a slide to carry said cross-head, and means to engage said guide upon said cross-head, substantially as set forth.

61. In a machine for generating the teeth of bevel-gears, a grinding-wheel having a reciprocatory movement in the operation of 30 grinding the gear, a housing to carry said wheel, a guide to carry said housing, a cross-head to carry said guide formed with an arc-shaped slot, and a slide to carry said cross-head, said guide formed with tongues projecting into the arc-shaped slot, substantially as described.

62. In a machine for generating the teeth of bevel-gears, means to carry a gear, a grinding-wheel reciprocatory on a cone line of the 40 gear in the operation of grinding the gear, and means to give a vertical adjustment to the grinding-wheel, whereby as it reciprocates it will reciprocate on a line passing through the cone center of the gear, substantially as set forth.

63. In a machine for generating the teeth of bevel-gears, means to carry a bevel-gear, a grinding-wheel having a series of reciprocatory movements on a cone line of the gear 50 in the operation of grinding the gear, and means to adjust the grinding-wheel whereby its cutting edge will be upon lines passing through the cone center of the gear both vertically and horizontally, substantially as set forth.

64. In a machine for generating the teeth of bevel-gears, means to carry a bevel-gear, a grinding-wheel, means to adjust the grinding-wheel whereby its cutting edge will be 60 upon a cone line of the gear, and a testing device to test the adjustment of said wheel, substantially as set forth.

65. In a machine for generating the teeth of bevel gears, means to carry a bevel-gear, a 70 grinding-wheel, means to adjust the grinding-wheel whereby its cutting edge will be upon a cone line of the gear, and a removable

bracket provided with a straight edge to test the adjustment of the grinding-wheel, substantially as described.

66. In a machine for generating the teeth of bevel-gears, means to carry a gear, a grinding-wheel, a lever to carry the grinding-wheel, means to adjust the grinding-wheel whereby its cutting edge will be on a cone line of the gear, a bracket to test the adjustment of the wheel, and a clamping-screw engaging said bracket upon said lever, said lever formed with V-shaped grooves to engage said clamping-screw, substantially as set forth.

67. In a machine for generating the teeth of bevel-gears, a device to carry a grinding-wheel having a reciprocatory movement in the operation of grinding the gear, said device 85 fulcrumed on a line passing through the cone center of the gear, substantially as set forth.

68. In a machine for generating the teeth of bevel-gears, a grinding-wheel, means to reciprocate the grinding-wheel on a cone line of 90 the gear in the operation of grinding the gear, and means to bring the edge of the grinding-wheel into contact with the teeth of the gear on a line passing through the cone center of the gear, substantially as described.

69. In a machine for generating the teeth of bevel-gears, means to carry a bevel-gear, and a rotatable grinding-wheel reciprocatory on a cone line of the gear in the operation of grinding the gear, substantially as set forth.

70. In a machine for generating the teeth of bevel-gears, means to carry a bevel-gear, and a rotatable grinding-wheel, means to reciprocate the grinding-wheel on a cone line of the gear in the operation of grinding the gear, 105 the means to carry the bevel-gear having a rocking movement in the operation of grinding the gear, substantially as set forth.

71. In a machine for generating the teeth of bevel-gears, means to carry a bevel-gear, a rotatable grinding-wheel and means to reciprocate the grinding-wheel on a cone line of the gear in the operation of grinding the gear, the means to carry the bevel-gear having a step-by-step movement, substantially as set forth.

72. In a machine for generating the teeth of bevel-gears, means to carry a bevel-gear, a grinding-wheel, means to give to the grinding-wheel a series of reciprocatory movements on a cone line of the gear in the operation of 120 grinding the gear, and means to adjust the grinding-wheel both vertically and horizontally, whereby its cutting edge will reciprocate on a cone line of the gear-teeth, substantially as described.

73. In a machine for generating the teeth of bevel-gears, means to carry a bevel-gear, a grinding-wheel arranged to have one lateral edge of its periphery actuate upon the gear upon the cone line of the gear, and means to 130 give to the grinding-wheel a series of reciprocatory movements on a cone line of the gear in the operation of grinding the gear, substantially as set forth.

74. In a machine for generating the teeth of bevel-gears, means to carry a bevel-gear, a lever oscillatory on a line passing through the cone center of the gear, a grinding-wheel carried by said lever, means to give to said grinding-wheel a series of reciprocatory movements on a cone line of the gear in the operation of grinding the gear, substantially as set forth.

75. In a machine for generating the teeth of bevel-gears, a grinding-wheel, a device to carry the grinding-wheel, a guide carrying said device, a reciprocatory cross-head carrying said guide, and means to limit the movement of the cross-head, said grinding-wheel having a reciprocatory movement in the operation of grinding the gear, substantially as set forth.

76. In a machine for generating the teeth of bevel-gears, a grinding-wheel having a rotary movement, means to give to the grinding-wheel a series of reciprocatory movements on a cone line of the gear in the operation of grinding a gear and a vertical movement, substantially as set forth.

77. In a machine for generating the teeth of bevel-gears, a rotatable grinding-wheel, and a rocking device to carry a gear to be cut, said gear and said grinding-wheel the one having a reciprocatory movement relative to the other in the operation of generating the teeth of the gear, substantially as set forth.

78. In a machine for generating the teeth of bevel-gears, a device to carry a bevel-gear, and a rotatable grinding-wheel having a tilting movement in relation to a plane passing through the center of the tooth being acted

upon and through the center of the axis of said gear, said wheel tilting from a point upon its periphery whereby its cutting edges can be brought into proper relation to said plane, 40 substantially as set forth.

79. In a machine for generating the teeth of bevel-gears, a device to carry a bevel-gear, a rotatable grinding-wheel reciprocatory on a cone line of the gear in the operation of grinding the gear, and means whereby the grinding-wheel will produce the proper curvature and the converging outline of the teeth of the bevel-gears, substantially as set forth.

80. In a machine for generating the teeth of bevel-gears, a grinding-wheel, means to rotate said wheel, means to reciprocate said wheel back and forth on a cone line of the gear at an angle to the longitudinal center of the axis of the gear, and means to reciprocate 55 the wheel on a radial line passing through the cone center, substantially as set forth.

81. In a machine for generating the teeth of bevel-gears, a rocking device to carry a bevel-gear, and a former to govern the movement of the gear, the central line of the former being coincident with a plane passing through the center of the tooth being acted upon, substantially as set forth.

In testimony whereof we sign this specification in the presence of two witnesses.

HENRY M. LELAND.
FRANK E. FERRIS.
